UNITED STATES PATENT OFFICE.

KARL VÖLLER, OF DUSSELDORF, GERMANY, ASSIGNOR TO RHEINISCHE METALL-WAREN- UND MASCHINENFABRIK, OF DUSSELDORF-DERENDORF, GERMANY.

DEVICE FOR AUTOMATICALLY OPENING THE BREECH OF A GUN WITH A RECOILING BARREL.

1,108,560.

Specification of Letters Patent. Patented Aug. 25, 1914.

Application filed January 17, 1907. Serial No. 352,766.

To all whom it may concern:

Be it known that I, KARL VÖLLER, engineer, a subject of the German Emperor, residing at 17 Jülicherstrasse, Dusseldorf, 5 Germany, have invented certain new and useful improvements in Devices for Automatically Opening the Breech of a Gun with a Recoiling Barrel; and I do hereby declare the following to be a full, clear, and exact 10 description of the invention, such as will enable others skilled in the art to which it applies to make and use the same.

This invention relates to a device for automatically opening the breech of a gun with 15 a recoiling barrel, in which the movement of the barrel in its recoil or return automatically turns the lever and thus opens the breech. In the known devices of this kind the lever has been moved by the recoiling 20 or returning barrel through the agency of a series of levers and rods. These latter, however, complicate the device and are uncertain in their action.

According to the present invention the 25 breech is opened by the return or recoil of the barrel automatically in a simple and certain manner; for this purpose a catch which holds the lever in the closing position engages in a guide which is so constructed 30 that at a certain position it causes a turning of the lever and thus the opening of the breech.

In the accompanying drawings several 35 modifications of the invention are shown by way of example.

Figures 1 to 6 show the application of the invention to a wedge shaped breech closure, Fig. 1 being a side elevation and Fig. 2 a rear view of the barrel on its cradle. Fig. 3 40 is a sectional plan showing the breech closed. Fig. 4 is a sectional plan showing the breech open. Figs. 5 and 6 show in sectional elevation and plan respectively a closing lever, drawn to an enlarged scale. Figs. 7 to 10 45 show a modification of the breech with wedge closure, Fig. 7 being a side elevation, and Fig. 8 a rear view of the barrel on its cradle; while Figs. 9 and 10 are sectional plans showing the breech open and closed 50 respectively. Figs. 11, 12 and 13 show the application of the invention to a breech op-

erated by a screw, Fig. 11 being a sectional rear view of the barrel on its cradle. Fig. 12 is a sectional plan thereof. Fig. 13 is a sectional view of a detail. Figs. 14 to 17 55 show a further modification for a wedge shaped closure, wherein the device for automatically opening can be put out of action. Fig. 14 is a side elevation, Fig. 15 a rear view, Fig. 16 a plan. Fig. 17 is also a plan, 60 the device being put out of action.

In the construction shown in Figs. 1-6, the recoil of the barrel is applied for automatically opening. The lever *a* is journaled in the breech, and is subject to the action 65 of a spiral spring *c* (Figs. 5 and 6) which tends to turn the lever into the opening position. In order to keep the breech closed when the barrel is at rest, a bracket *d* is fixed to a side of the cradle and in this 70 bracket there is a groove *e* open at its rear end, and running parallel to the axis of the barrel. When the breech is closed, the catch or pin *g* of the handle lock *f* engages in this groove *e*, so that automatic opening is impossible, while by gripping the lock *f* by hand, and then turning the lever, opening can be effected. When the barrel recoils, the pin 75 *g* is guided in the groove *e* until the shot and the products of explosion have left the 80 barrel. The length of the groove *e* is fixed to suit these firing conditions. As soon as the pin *g* has left the groove *e*, the lever becomes turned into the opening position by the spiral spring *c*, so that the breech opens. 85 When the barrel returns, the next shot is introduced into the breech and the wedge *b* is closed by gripping the lock *f* and turning the lever until pin *g* can again spring into the groove *e*. In determining the length of 90 the groove *e* it must be remembered that after prolonged firing, the barrel does not return completely to its original foremost position, so that the backward travel of the pin *g* may be somewhat shorter than that 95 necessary to take it to the end of the groove *e*. This fact need not detract from the usefulness of the construction if the groove *e* is made long enough to insure that the wedge only opens when the products of explosion 100 have left the barrel.

In the form shown in Figs. 7-10 the re-

turn of the barrel is utilized for automatically opening. In this case also the pin *g* of the handle lock *f* slides in a groove *e'* in the bracket *d*. This rectilinear groove *e'* is open at its rear end, but not freely open. It rises gradually rearwardly (Fig. 7) so that the pin *g*, when the barrel recoils, slides without hindrance over the rear end of the groove. In this case the lever is not subject to the action of the spiral spring so that it is not turned when the pin *g* has left the groove *e'*. When the barrel returns, the pin *g* enters a curved groove *h* in the surface of the bracket *d*. The outer end of the groove *h* is in the same straight line as the groove *e'*, and owing to its curved form the pin *g* is deflected in such a manner that the lever *a* is turned and the breech opened. (Fig. 10). The curve of the groove *h* is such that the opening is complete before the end of the return movement.

Figs. 11-13 show the invention as applied to a screw lock. In this case the lever *i* has a toothed wheel *k* on the lower end of its pivot, which engages with a toothed segment *l*. This toothed segment turns on a pivot in an extension *m* of the breech, and is provided with a vertical spring pin *n*. This pin engages in a curved groove *o* and is turned by this so that the toothed segment turns through an angle of 90°. By means of a toothed wheel *k* this turning movement is transmitted to the lever *i*. The front end of the groove *o* is made to slope upward toward the axis of the barrel as shown in Fig. 13, so that when the lever *i* is turned into the closing position the pin *n* automatically lifts itself on to the surface of the bracket *p*, over which it can slide during the recoil of the barrel.

The forms shown in Figs. 14-17 corresponds in essential details to that shown in Figs. 7-10. It differs from that form, however, in that the device for automatic opening may be put out of action when this is desirable. For this purpose the rear part *d'* of the bracket *d* is pivoted on the pin *q*. The rear parts of the groove *e'* and of the curved groove *h* are carried on this piece *d'*. The latter is fixed in the horizontal position by means of a spring bolt *r*, which extends through the immovable part of the bracket *d* and through a perforation *s* in an arm *t* fixed to the piece *d'*. When the bolt *r* is withdrawn, the piece *d'* falls into the position shown in dotted lines in Figs. 14 and 15, in which position it is held by the springing of bolt *r* into the perforation *u* in the arm *t*. When the piece *d'* is turned down into the position shown in Fig. 17 and in dotted lines in Fig. 14, the pin *g* returns into the groove *e'* when the barrel returns and the lever remains in the closing position. In this case opening

must be effected by hand, by gripping the lever *a* so as to lift the pin *g* out of the groove by means of lock *f*.

Having now particularly described and ascertained the nature of my said invention and in what manner the same is to be performed, I declare, that what I claim is:

1. In a device for automatically opening the breech of a gun having a recoiling barrel, the combination with a closing lever, of a locking device mounted on the hand⁷⁰ end of the closing lever, a two-part guide for the closing lever hinged together by a horizontal pin and adapted to be engaged by the locking device, a detachable bolt for securing the two parts of the guide in an operative position, said guide arranged to operate the closing lever at a certain position of the barrel.

2. In a breech-opening device for guns having a recoiling barrel, the combination, ⁸⁵ with a closing lever, of a locking device mounted on the closing lever, a guide member mounted to swing downward about an axis transverse to the axis of the gun and arranged to be engaged by said locking device when in its elevated position, the guide member being arranged when elevated to operate the closing lever during counter-recoil, and releasable means for locking said swinging guide member in its elevated position. ⁹⁰

3. In a breech-opening device for guns having a recoiling barrel, the combination with a closing lever, of a locking device mounted on said lever, a horizontal pin ¹⁰⁰ whose axis is transverse to the axis of the gun, a swinging guide member hinged on the horizontal pin having its axis transverse to the axis of the barrel, said guide-member when in its elevated position being engaged by said locking device, the guide member arranged when elevated to operate the closing lever to open the breech during counter-recoil. ¹⁰⁵

4. In a breech-opening device for guns having a recoiling barrel, the combination with a closing lever, of a locking device mounted on the lever, a swinging guide member hinged on a horizontal pin having its axis transverse to the axis of the barrel, ¹¹⁵ said guide-member when in its elevated position being engaged by the locking device, a detachable bolt to secure said guide member in its adjusted elevated position, the guide member arranged when elevated to operate the closing lever to open the breech during counter recoil. ¹²⁰

5. In an automatic breech opening device for guns, the combination of a bracket having a stationary and a swinging part and having guide grooves in the upper surface of said parts, a breech operating lever, and a locking pin mounted in said lever ¹²⁵

and engaging the guide grooves; the said grooves being arranged when the swinging part of the bracket is raised to hold the lever normally in its closed position and to 5 throw the same to the open position during the movement of the barrel of the gun due to recoil and return.

In testimony whereof I have hereunto affixed my signature in the presence of two witnesses.

KARL VÖLLER.
